United States Patent Office

Des. 176,701
Patented Jan. 17, 1956

176,701

HANDBAG

Harry T. Silverman, Forest Hills, N. Y.
Application July 19, 1955, Serial No. 37,035

Term of patent 3½ years
(Cl. D87—3)

FIG. 2.

FIG. 1.

FIG. 4.

FIG. 3.

Fig. 1 is a front elevational view of a handbag showing my new design;

Fig. 2 is a side elevational view thereof;

Fig. 3 is a rear elevational view; and

Fig. 4 is an enlarged detail view of a portion showing the perforated body casing.

I claim:

The ornamental design for a handbag, substantially as shown.
